Arthur J. Bennett, ^{Inventor}
By W. H. Mays, ^{Attorney}

UNITED STATES PATENT OFFICE.

ARTHUR J. BENNETT, OF CAMBRIDGE, OHIO.

DESIGN FOR A FLOWER-HOLDER.

48,166.

Specification for Design.

Patented Nov. 23, 1915.

Application filed May 24, 1915. Serial No. 30,204. Term of patent 7 years.

To all whom it may concern:

Be it known that I, ARTHUR J. BENNETT, a citizen of the United States, residing at Cambridge, in the county of Guernsey and State of Ohio, have invented a new, original, and ornamental Design for a Flower-Holder, of which the following is a specification, reference being had to the accompanying drawing, forming part thereof.

Figure 1 is a top plan of a flower holder, showing my new design; and Fig. 2 is a side elevation of the flower holder shown in Fig. 1.

I claim:

The ornamental design for a flower holder, as shown.

ARTHUR J. BENNETT.

Witnesses:

FRED RICKY,
JENNIE NOBLE.
